(57) CLAIM

The ornamental design for a quarter fender for a truck vehicle, as shown and described.

DESCRIPTION

FIG. 1 is a perspective view of a first embodiment of a quarter fender for a truck vehicle;

FIG. 2 is a front view thereof;

FIG. 3 is a top view thereof;

FIG. 4 is a bottom view thereof;

FIG. 5 is a right side view thereof;

FIG. 6 is a left side view thereof;

FIG. 7 is a second perspective view thereof;

FIG. 8 is a perspective view of a second embodiment of a quarter fender for a truck vehicle;

FIG. 9 is a front view thereof;

FIG. 10 is a top view thereof;

FIG. 11 is a bottom view thereof;

FIG. 12 is a right side view thereof;

FIG. 13 is a left side view thereof; and,

FIG. 14 is a second perspective view thereof.

Parts shown in broken lines are for illustrative purposes only and form no part of the claimed design.
